UNITED STATES PATENT OFFICE

2,571,178

SELECTIVE BELL CLAPPER SILENCER

William Merrill Allen, Glendale, Ohio, assignor
to Sidney B. Merrill, Cincinnati, Ohio

Application August 23, 1950, Serial No. 181,027

6 Claims. (Cl. 177—288)

1

My invention relates to a bell silencer for use with bells having a clapper swingable in a single plane to ring the bell. Bells of this type include church bells which are hung in the bell tower of a church and are supported by a yoke which permits swinging of the bell in a single plane. The clapper or tongue is hung from the ear of the bell and consists of a clapper pendant terminated by the clapper itself. When the bell is swung, the clapper contacts the sound-bow of the bell which produces the strike or ring.

In bells of this type and particularly church bells, it is often desirable to toll the bell. At the present time, this tolling or single strike is accomplished by striking the outside of the bell on the sound-bow to produce a single toll or strike. When tolling the bell in this manner, the bell is stationary and the mouth of the bell projects downwardly and thus the sound or note of the bell travels downwardly into the church below and not out over the surrounding country, as is desirable.

In playing chimes or carillons on a series of bells wherein they are swung to produce the strike, it is extremely difficult to control the swing so that specified sequences of notes may be played, since it is necessary to build up the swing of a bell before the clapper will hit the sound-bow and produce the ring.

It is an object of my invention to provide a bell silencer which is attached to the clapper pendant of the bell and which prevents the ringing of the bell by the clapper contacting the sound-bow, although the bell itself is being vigorously swung. By this means, the bell is swung until it reaches its top swing, and the clapper is only permitted to contact the sound-bow and produce a ring at the will of the operator.

It is a further object of my invention to provide a bell silencer which permits tolling of a bell or the striking of a single note with the bow of the bell in its swung position.

It is a further object of my invention to provide a bell silencer which will permit full and continuous swinging of a single bell or of a plurality of bells of different tones and permit the controlled striking of a single or numerous bells at the will of the carillonneur. By this means, definite tones or controlled sequences of notes may be played, such as the ringing of the Angelus and the like.

It is a further object of my invention to provide a bell silencer which may be easily and quickly fitted to the clapper pendant of a bell

2

already hung without the necessity of disassembling or dismounting the bell at all.

It is a further object of my invention to provide a bell silencer which is extremely rugged in construction and can withstand the constant impact or swinging of the bell without getting out of order or adjustment.

A further object of my invention is to provide a bell silencer which is relatively inexpensive to construct and which may be adapted without complicated adjustments to different sizes and forms of bells.

In the drawing and description, I show and describe my bell silencer used with a bell spring similar to that shown and described in the co-pending application of Sidney B. Merrill, filed May 23, 1950 Serial No. 163,737 entitled Bell Spring.

However, it is to be understood that my bell silencer with slight modification may be used without the bell spring referred to.

These and other objects of my invention which will be set forth hereinafter or will be apparent to one skilled in the art upon reading these specifications, I accomplish by that certain construction and arrangement of parts of which I shall now describe an exemplary embodiment. Reference is now made to the drawings which form a part thereof and in which:

Figure 1 is a plan view of my novel bell silencer with a portion broken away to show the underlying features.

Figure 2 is a side elevation of my bell silencer with a portion broken away and a portion in section. In this figure the silencer is in position to prevent the clapper from striking the sound bow.

Figure 3 is a side elevation similar to that shown in Figure 2, but with the silencer in position to permit the clapper to strike the sound bow.

Figure 4 is a plan view of a portion of my bell silencer.

Figure 5 is a cross section of a bell at the top of its swing showing my bell silencer in operative position to prevent the clapper from striking the sound bow.

Figure 6 is a cross section of a bell at the top of its swing similar to Figure 5, but with the bell silencer in position to permit the clapper to strike the sound bow.

Briefly, in the practice of my invention I provide a bell clapper silencer which consists of opposed springs projecting from opposite sides of the clapper pendant and in the plane of the swing of the clapper. These springs are mount-

ed on a mechanism attached to the clapper pendant which normally projects the springs outwardly to an extent where they will prevent the clapper striking the sound bow of the bell. A separate mechanism is provided for each spring which upon the actuation of a switch permits the spring to give when it contacts the barrel of the bell and thus permits the clapper to strike the sound bow.

In the modification shown and described, a torque solenoid is mechanically connected to the mechanism which controls the extension and retractability of each of the two springs and are connected through individual circuits to a switch remote from the bell. When both switches are open and the bell itself is swinging, the clapper is prevented from contacting the sound bow, since the springs contact the bell barrel and hold the clapper away. When it is desirable to form a single strike or toll, the bell is swung until it gets up to its ringing swing and then one of the switches is closed for an instant which permits the spring to retract and the clapper to contact the sound bow in a single strike. It should be noted that this strike occurs while the bell is at the top of its swing.

If it is desirable to let the bell ring freely, both switches are closed which permits both springs to retract and the clapper to strike the sound bow at will.

In the drawings and description which follows, I have illustrated and described a single spring and its actuating mechanism including the torque solenoid. However, it is to be understood that there is a similar spring projecting from the other side of the clapper pendant in the plane of the clapper swing which is identical in all particulars with the one shown and described.

Referring to the drawings, the bell 1 includes the sound bow 2 against which the clapper 3 strikes to produce the ring. The clapper 3 is mounted on the clapper pendant 4, and it is only permitted to swing in a single predetermined plane with the swinging of the bell 1 on its yoke 5.

Mounted on the clapper pendant 4, I provide a bracket 6 which may be removably bolted by bolts 7 to the clapper pendant or which may be directly welded to the pendant itself so as to form a part thereof.

When the bolts 7 are used, the device may be adjusted both around the clapper pendant 4 and up and down the pendant so that the mechanism will contact the barrel 8 of the bell at the proper spot and not dampen the tone of the bell. The mouth of the bell is shown at 9.

The bracket 6 includes an integral upstanding boss or stud 10. The boss 10 is encircled by a rotatable disc 11 of appreciable thickness and which has inwardly projecting teeth 12.

Encircling the boss 10 beyond the disc 11 is a bracket 13 which has downwardly projecting teeth 14 which will register with the teeth 12 of the disc 11 when the disc is in one position and slide between the teeth 12 when the disc 11 is in a second position.

The bracket 13 is mounted on upstanding bolts 14a which are screwed into a plate 15, which in turn is bolted to the bracket 6 by the screws 16.

The bracket 13 is urged away from the plate 15 by springs 17 of relatively light resistance. On the upper side of the bracket 13 is a cup shaped socket 18 which carries a heavy helical spring 19, which also encircles a portion of the stud 10.

The spring 19 is held in position within the cup 18 by means of a set screw 20.

On a part of the plate 15 is positioned a torque solenoid with an arm 22 mounted on the armature 23. There is a link 24 from the end of the arm 22 to a pin or bolt 25 on the periphery of the disc 11. I also provide a stop pin 26 on the plate 15 which projects within a peripheral slot 27 cut in the disc 11. The positioning of the pin 26 is such that when the disc 11 is rotated until the pin is at one end of the slot 27, the teeth 12 of the disc 11 and the teeth 14 of the bracket 13 are in registry, thus preventing the movement of the bracket 13 against the springs 17. When the disc 11 is rotated so that the pin 26 is at the other end of the slot 27, the teeth 14 of the bracket 13 will clear the teeth 12 of the disc 11 and the bracket 13, together with the helical spring 19, may be moved down the stud 10 against the pressure of the springs 17. If desirable, the stop may be incorporated in the torque solenoid instead of using the pin 26 and slot 27.

The positioning of the torque solenoid 21 is such and its linkage with the disc 11 is such that when the solenoid 21 is unenergized, the disc 11 will be so positioned as to prevent the movement of the bracket 13 with helical spring 19 down the stud 10. This position is maintained by a spring 28 between the plate 15 and the strap 24. However, when the solenoid is energized, the movement of its armature 23 will revolve the disc 11 to its second position so the teeth 12 and 14 will clear each other and so the bracket 13 and the helical spring 19 may be moved down the stud 10.

The solenoid 21 is included in an electrical circuit having a switch 29 and another similar solenoid which actuates the opposite mechanism is included in an electrical circuit having a similar switch, and the whole device is mounted on the clapper pendant 4 in such a position that when the clapper 3 is swung the end 19' of the spring 19 will contact the barrel 8 of the bell and prevent the clapper 3 from striking the sound bow 2 unless the bracket 13 carrying the spring 19 is permitted to move down on the stud 10.

Figures 5 and 6 show these different conditions. In Figure 5, the solenoid 21 is unenergized and the spring 19 is preventing the clapper 3 from contacting the sound bow 2 of the bell. In Figure 6, the switch 29 is closed, which has energized the solenoid 21 moving the disc 11 and permitting the spring 19 to force the bracket 13 against the relatively weak pressure of the springs 17 so the clapper 3 will strike the sound bow of the bell.

If it is desirable to produce a single strike or a toll of the bell, it is first swung with the switches 29 left open so the clapper 3 may not contact the sound bow 2. When the bell has reached its predetermined swing, one of the switches 29 is closed and the clapper 3 contacts the sound bow producing a single strike or the toll. Since the switch 29 is immediately opened, the result is a single strike.

In the event it is desirable that the bell ring freely, both switches 29 are held closed, and this permits the spring 19 to be moved towards the clapper pendant 4 and the bell is freely rung as if the silencer were not present.

From the above, it is apparent that by actuating the switches 29, any series or spacing of strikes may be accomplished such as a single toll or the playing of the Angelus. At the end of the

Angelus when the bells are to ring freely, both contacts or switches 29 on the bell are held closed.

While I have shown my bell silencer as being mounted on a removable bracket 6, it is to be understood that it is within the contemplation of my invention to incorporate my silencer into the clapper pendant 4 of the bell as a permanent part thereof.

While I have shown torque solenoids for controlling the movement of the disc 11, other mechanisms either mechanical or electrical could be used to accomplish this purpose.

It is to be particularly noted that the bell is always rung when it is at the top of its swing as shown in Figures 5 and 6 and the bell may be tolled by this method which insures the mouth 9 projecting at an angle to the vertical and thus throwing the sound away from the structure underlying the bell.

It is to be understood that modification may be made in my invention without departing from the spirit thereof, and I do not intend to limit myself otherwise than as pointed out in the claims which follow.

Having thus described my invention, what I claim as new and desire to secure by Letters Patent is:

1. In a bell having a clapper swingable in a single plane, a damper comprising oppositely opposed projecting helical springs mounted on the clapper pendant within the plane of its swing, said springs being of sufficient length to contact the bell barrel and prevent the clapper from striking the sound bow of the bell and selective means permitting the retraction of said springs selectively to permit the clapper to strike the sound bow.

2. In a bell having a clapper swingable in a single plane, a damper comprising oppositely opposed projecting helical springs mounted on the clapper pendant within the plane of its swing, said springs being of sufficient length to contact the bell barrel and prevent the clapper from striking the sound bow of the bell and selective means permitting the retraction of said springs selectively to permit the clapper to strike the sound bow, said springs being mounted on a bracket slidably mounted on projecting studs and resiliently urged away from the clapper pendant and said means comprising a rotatable disc mounted on said stud between the spring holding bracket and the clapper pendant, inwardly projecting teeth on said disc and downwardly projecting teeth on said bracket, said teeth being arranged so that at one position of the disc they will register and block the movement of the bracket, while at another position of the disc they will permit the intermeshing of the teeth and the movement of the bracket towards the clapper pendant.

3. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and adjustable means on said studs to selectively prevent and permit the sliding of said spring holding bracket on its stud to prevent and permit

the clapper to strike the sound bow and ring the bell.

4. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 10 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 15 the teeth of the bracket and permit its movement on the stud.

5. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 20 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 25 the teeth of the bracket and permit its movement on the stud.

6. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 30 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 35 the teeth of the bracket and permit its movement on the stud, and a torque solenoid operatively attached to each disc for revolving them to their different positions.

7. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 40 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 45 the teeth of the bracket and permit its movement on the stud, and a torque solenoid operatively attached to each disc for revolving them to their different positions.

8. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 50 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 55 the teeth of the bracket and permit its movement on the stud, and a torque solenoid operatively attached to each disc for revolving them to their different positions.

9. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 55 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 60 the teeth of the bracket and permit its movement on the stud, and a torque solenoid operatively attached to each disc for revolving them to their different positions.

10. In combination with a bell having a clapper adapted to be swung in a single plane, a bell spring and silencer comprising oppositely opposed studs projecting from the clapper pendant in the plane of its swing, a spring holding bracket slidably and non-rotatively mounted on each stud and resiliently urged away from the clapper pendant by relatively weak springs, relatively heavy helical bell springs mounted on said bracket and projecting in the plane of swing and of sufficient length to contact the bell barrel before the clapper contacts the sound bow, and 65 adjustable means on said studs to selectively prevent and permit the sliding of said spring holding bracket on its stud to prevent and permit the clapper to strike the sound bow and ring the bell, said adjustable means comprising a revolvable disc surrounding each stud and having inwardly projecting teeth which in one position of the disc register with downwardly projecting teeth on the spring holding bracket and prevent its movement and in another position mesh with 70 the teeth of the bracket and permit its movement on the stud, and a torque solenoid operatively attached to each disc for revolving them to their different positions.

its movement on the stud, and a torque solenoid having its armature linked to each disc so that when the solenoid is unenergized the teeth will register and the bell be silent and when energized the teeth will mesh and the bell ring, and a switch for each solenoid remote from the bell.
